(57) **CLAIM**

The ornamental design for a dashboard for motor vehicle as shown and described.

DESCRIPTION

FIG. 1 is a perspective view of a dashboard for motor vehicle showing my new design;

FIG. 2 is a front view thereof;

FIG. 3 is a right view thereof;

FIG. 4 is a left view thereof; and,

FIG. 5 is a top view thereof.

The broken lines illustrate portions of the dashboard for motor vehicle that form no part of the claimed design.
